United States Patent Office.

WESLEY S. POULSON, OF CADIZ, OHIO.

Letters Patent No. 90,870, dated June 1, 1869.

IMPROVEMENT IN BOOK-HOLDERS.

The Schedule referred to in these Letters Patent and making part of the same.

To all whom it may concern:

Be it known that I, WESLEY S. POULSON, of Cadiz, in the county of Harrison, and State of Ohio, have invented a new and valuable Improvement in a Combined Book-Holder and Pen-Rack; and do hereby declare that the following is a full, clear, and exact description of the construction and operation of the same, reference being had to the annexed drawings, making a part of this specification, and to the letters and figures of reference marked thereon.

Figure 1 of the drawings is a plan view of my device, and

Figure 2 is a section thereof, showing the ratchet *d* and pawl *s*, hereinafter described.

My invention relates to devices intended for a school-room library or office; and

It consists mainly in providing more perfect and efficient means than have heretofore been known for holding an open book, for reading or copying.

The letter *A* of the drawings represents a board cut out in the centre and at one end, in the form shown, and having a cross-bar, or rest, *a*, fastened across its open end.

B is a door, hinged or pivoted, near its lower end, to the board *A*, as shown, and, when closed, resting its upper end upon the cross-bar *a*.

The letters *c* are pins, with bolt-heads, driven into the door *B*, at the point indicated, which serve as a support for the bottom of the book.

C is a wire, bent in the form of a coiled spring at

each end, and which said coiled ends are adjusted in openings formed for that purpose in the door *B*.

After being thus coiled at each end, said wire is bent upward, in the form of a half circle, and made to lie, when not in use, about half an inch, more or less, from the surface of the door *B*.

The book to be held is placed, with open leaves, between the half circle of the wire so formed and the surface of the door *B*.

This door is raised or lowered at will, from the cross-bar *a*, and it is secured in any desired position, by means of a ratchet, *d*, adjusted on its side, as shown, working in conjunction with the pawl *s*.

A pen-rack, *H*, is shown on the drawings.

The operator places his book under the wire *C*, and adjusts the door, by its ratchet and pawl, to suit his convenience.

What I claim as my invention, and desire to secure by Letters Patent, is—

The book-holder, herein described and shown, when constructed with board *A*, door *B*, cross-bar *a*, pins *c*, coiled wire *C*, ratchet *d*, and pawl *s*, arranged and operating substantially as specified.

In testimony that I claim the above, I have hereunto subscribed my name, in the presence of two witnesses.

WESLEY S. POULSON.
